UNITED STATES PATENT OFFICE.

IRWIN STEINBERGER, OF NEW YORK, N. Y.

GLOVE.

Application filed March 29, 1927. Serial No. 179,260.

This invention relates to gloves and has for an object to provide an improved fastener for slip-on gloves wherein a proper clamping action is secured and at the same 5 time a pleasing appearance presented.

A further object of the invention is to provide a fastener for slip-on gloves, which absolutely secures the gloves in place and makes the gloves look more slightly.

10 A further object, more specifically, is to provide a fastener for gloves, wherein the fastening buckle or member may be threaded by a back and forth movement of the strap carried by one hand.

15 In the accompanying drawing—

Figure 1 is a plan view of a glove, disclosing an embodiment of the invention, the same showing the fastener in its fastened or functioning position.

20 Figure 2 is a view similar to Figure 1, except that the fastener is shown disconnected.

Figure 3 is a plan view of the fastener clip or buckle.

Figure 4 is an edge view of the buckle 25 shown in Figure 3.

Figure 5 is a fragmentary sectional view through Figure 2 on line 5—5.

Referring to the accompanying drawing by numerals, 1 indicates the body of a glove, 30 which glove is of the usual slip-on type. In order that the glove may be properly fastened on the hand, a fastening strap 2 is provided which extends around the wrist of the glove and acts to fasten the glove in 35 place when in use. The fastener strap 2 is an ornamental strap, shown as a platted strap with a single end section 3. If desired, the strap could be of some other formation, as for instance, an ordinary straight

40 strap. In forming the strap 2, certain parts are formed to present a loop 4, said loop being looped over the central bar 5 of the fastener clip or buckle 6. The fastener clip or buckle is not only formed with a bar 5 but 45 with side members 7 and 8 merging into end members 9 and 10 substantially parallel with the bar 5 whereby oppositely facing notches 11 and 12 are presented. The loop 4 fits over the bar 5 and is permanently connected

50 to bar 5 by lines of stitching 13. Also, lines of stitching 14 are provided which extend through the strap 2 near stitches 13 and also through part of the glove body 1 whereby the buckle 6 and associated parts will always 55 remain in the same place, which is preferably centrally of the back of the glove. The

glove body 1 is also provided with any desired number of loops 15, stitched or otherwise secured to the glove body for presenting guiding supports for the strap which is 60 threaded therethrough.

When the device is to be placed on the hand, the end section 3 is preferably disengaged and moved to substantially the position shown in Figure 2. The hand is then 65 placed in the glove and the glove adjusted to the desired position, after which, the end section 3 is grasped by the free hand, moved slightly to one side and then back into the notch 11. It is then moved over the bar 5, 70 to one side, and then back into the notch 12 as shown in Figure 1. After this has been done, the extreme end of the end section 3 is placed beneath the keeper 16 and the fastening operation has been completed. In performing this fastening operation, the desired 75 tension is maintained on the strap or it is secured immediately after it is fitted into slot 11, as the fitting into slot 12 binds the parts, and under ordinary circumstances, there will be no movement so that the device secures the glove properly in place and presents in addition, a very pleasing wrist band.

To remove the glove, the end 3 is removed from keeper 16, shifted to one side and 80 raised so as to move the same from the slot 12, shifted to the other side until it is removed from slot 11, and then thrown back to the position shown in Figure 2. After 85 the strap has been thus unfastened, the glove 90 may be removed in the usual manner.

What I claim is:

A glove and fastener, comprising a slip-on glove structure, a strap guiding loop secured to the glove structure near one side thereof, 95 a contracting strap for the glove structure normally positioned to extend loosely through said loop, a buckle structure operatively connected with one end of the strap, said buckle structure having oppositely extending openings for successively receiving the free end of said strap for locking said free end in operative association with the secured end of the strap, a strap keeper mounted on the strap near said buckle, and stitching securing the buckle end of said strap to the back of the glove body near the center thereof, the opposite end of said strap being interlocked with said buckle structure and extending through said strap keeper 100 whereby the strap is held under tension.

IRWIN STEINBERGER.
